ARCHED METALLIC CULVERT

Albert F. Fischer, Mason City, Iowa

Application July 13, 1931. Serial No. 550,540

1 Claim. (Cl. 137—75)

The object of this invention is to provide an improved construction for a metallic culvert of arched or substantially semi-cylindrical section whereby capacity is provided for a comparatively 5 large flow of water as compared with the capacity of the usual type of circular or cylindrical culvert employing a similar amount of material.

A further object of the invention is to provide an improved metallic culvert employing a unitary flanged base frame and arched metallic sheets set loosely or removably in the base frame in such manner that the tendency of the sheets to spread laterally is resisted by the flanges thereof.

Still another object of the invention is to provide an improved arched metallic culvert which is characterized by economy of cost for material and installation, which provides capacity for a large flow of water in proportion to the amount 20 of material employed, and so arranged that the arch may be readily taken up for removing debris, trash and other accumulations from the water-way without disturbing the frame work.

With these and other objects in view my invention consists in the construction, arrangement and combination of the various parts of my device, whereby the objects contemplated are attained, as hereinafter more fully set forth, pointed out in my claim, and illustrated in the 30 accompanying drawing, in which:—

Figure 1 is a side elevation, partly in section, of one form of my improved metallic culvert.

Figure 2 is an enlarged cross section on the line 2—2 of Figure 1.

Figure 3 is a cross section illustrating a modified form including the use of floor plates between the base frame and arch.

Figure 4 is a cross section of a further modified form in which the base frame is formed integrally with floor plates.

My invention in all of its embodiments involves the use of a unitary structural base frame adapted to be constructed and laid horizontally in a trench or other location for the culvert, the base frame being formed with upturned flanges at its side margins within which arched metallic sheets are placed, the flanges of the base frame serving to take the thrust of the arch and to resist the 50 tendency toward lateral spreading of the arched sheets. The arch is preferably formed of corrugated metal sheets which may be set loosely in the flanged base frame or at any rate are removably mounted on the base frame to permit them 55 to be taken up at times for cleaning the water-

way and removing accumulations of debris, trash, sand or mud.

In the form shown in Figures 1 and 2 the base frame is composed of a pair of spaced angle iron sills 10 and 12 which face toward each other, or 60 in other words are arranged with their vertical flanges extending upwardly and on the outer sides of the horizontal flanges whereby a flanged seat for the arch is provided. The sills 10 and 12 are mounted on and fixed to a plurality of cross bars 14 which also are preferably composed of angle irons and are arranged with their horizontal flanges engaging the lower faces of the horizontal flanges of the sills and secured thereto by rivets 16. The vertical flanges of the cross bars 65 14 extend downwardly and have the function of engaging the earth upon which the culvert is placed, thereby preventing longitudinal movement of the base frame.

The arch of the culvert is composed of one 75 or more metallic sheets 18 preferably corrugated transversely as shown. The sheets 18 may be mechanically shaped to the desired curvature to form an arch of substantially semi-cylindrical cross section or somewhat less, or they may be 80 bent transversely at the time of placing them in the base frame and be held against their tendency to spread laterally by the engagement of their lateral sides with the upstanding flanges of the sills 10 and 11. In any event the thrust on 85 the arch because of the weight of superposed earth on the culvert is carried by the flanged side sills of the base frame.

In the event that a plurality of sheets 18 are 90 employed in a single culvert, the sheets may overlap slightly at their ends to form lap joints 20.

In the form shown in Figure 3 the base frame and arch are composed of members like those previously described in connection with Figures 1 and 2. The only difference in the culvert construction illustrated in Figure 3 is that a floor plate 22 is provided for the culvert. The floor plate 22 may be composed of a metallic sheet or a series of sheets carried by the base frame and 95 preferably mounted on the cross bars 14 below the sills 10 and 12 and conjunctively secured thereto by rivets 16.

As illustrated in Figure 3 the arched culvert sheets 18 may be removably secured at their side margins to the sills 10 and 12 by means of bolts 24 instead of being set loosely in said sills. It is to be understood that if desired bolts such as 24 may be employed in any of the embodiments of my invention, but that ordinarily it is not necessary to employ such securing means.

In the form shown in Figure 4 a floor plate also is employed but it is formed integrally with the sills, or, more accurately speaking, the base plate is formed with upturned flanges at its side 5 margins to constitute a seat for the arched culvert sheets.

In this form of the device I employ the angle iron cross bars 14 as before and on these cross bars is supported a metallic floor plate 26, secured to the cross bars by rivets 28. The floor plate 26 is formed at its side margins with upturned flanges 30 and 32 which are engaged by the side margins of the arched sheets 34. Figure 4 also illustrates that the arched sheets may be 10 materially flatter or of less vertical height than as illustrated for instance in Figure 2, and it will be readily understood that various modifications in this respect may be employed to suit various 15 conditions.

20 There is a considerable advantage so far as economy of material is concerned in making a culvert of semi-cylindrical or arched formation as compared with a truly cylindrical structure or 25 multiple structure of the same capacity and utilizing the same head room.

My method of supporting the arched culvert sheets by means of a flanged base frame is highly 30 advantageous because it greatly reduces the amount of labor required for installation and furthermore it provides an efficient and inexpensive 35 means for supporting the arch. The base frame is a unitary construction and may be built in the factory to the required dimensions and may then be easily and quickly set in place at the desired location after which the arched sheets can be

easily and quickly put in place so that all parts of the culvert are held in the desired positions.

It should also be noted that by setting the arch loosely in the flanged base frame or by attaching it removably by means of the bolts 24, it is a 80 comparatively easy matter to remove the arch upon occasion for cleaning the waterway of accumulations of debris, sand or mud without disturbing the base frame in any way. This feature is especially desirable where a wide waterway with low head room is required for city and 85 town drainage purposes.

Some changes may be made in the construction and arrangement of the parts of my device without departing from the real spirit and purpose of my invention, and it is my intention to cover by 90 my claims, any modified forms of structure or use of mechanical equivalents, which may be reasonably included within their scope.

I claim as my invention:—

An arched metallic culvert structure comprising a fabricated unitary base frame composed of a pair of spaced side sills having upstanding flanges at their outer margins, a plurality of spaced bars secured at suitably selected intervals to the sills and rigidly connecting the same, said cross bars having downturned flanges for gripping the ground and for reenforcing the base frame, and an arch composed of one or more metal sheets superposed on the base frame and 100 having their side margins disposed against the upturned flanges of said sills which thereby receive the thrust of load on said sheets and serve to retain the sheets in arched position.
